UNITED STATES PATENT OFFICE.

DOUGLAS BREWS, OF CLEVELAND, OHIO

BLOW-OUT DEVICE FOR BOILER-FLUES.

1,192,162.

Specification of Letters Patent. Patented July 25, 1916.

Application filed April 20, 1914. Serial No. 833,189.

To all whom it may concern:

Be it known that I, DOUGLAS BREWS, a citizen of the United States, residing at Cleveland, in the county of Cuyahoga and State of Ohio, have invented certain new and useful Improvements in Blow-Out Devices for Boiler-Flues, of which the following is a specification.

This invention has reference to blow-out devices for steam boiler flues, all substantially as shown and described and particularly pointed out in the claims.

In the accompanying drawings, Figure 1 is a front elevation of a flue boiler installation provided with my new and improved blow-out mechanism. Fig. 2, next above Fig. 1, is a plan view of Fig. 1, showing the front portions of the boiler and my invention therewith. Fig. 3 is a side elevation of Fig. 2, and Fig. 4 is an enlarged sectional elevation thereof, and Fig. 5 is a detail.

The invention as thus shown is an improvement upon my own invention as disclosed more particularly in Letters Patent No. 881,895, of March 17, 1908, and is designed to overcome and remedy certain defects in that construction and to which experience has demonstrated to be desirable and material, and is especially desirable for marine boiler installations of the larger and more modern type, in which there are the usual boiler flues 2 and draft flues 6 relatively in front of and above the same and at right angles thereto as most clearly shown in Figs. 3 and 4. The chief improvement herein lies in the combined mechanism adapted to blow out both sets of tubes simultaneously through the medium of a single steam supply pipe and a single simple hand operated mechanism.

To these several ends I provide a single steam distributing pipe indicated by 4 and a plurality of vertically disposed branch pipes 3 at the front of boiler tubes 2 and provided with nipples 5 in position to come centrally opposite said tubes in any lateral movement of the said pipes 3 so that different vertical series of tubes may be successively cleansed as the pipes are moved laterally over the same for this purpose. If the said tubes occupy a total width greater than the range of lateral adjustment of single pipes 3 I may employ two such pipes in successive positions as seen at both right and left in Fig. 3, and a relatively longer pipe 3 can be used as at the middle of said view if

the tubes 2 occupy greater depth than width. It will not matter if one of the follower pipes at right and left does traverse a portion of the area covered by the preceding pipe, and of course the adjustment or movement of said pipes is only at intervals and of comparatively short duration when used as their work is exceedingly effective under the high head of steam usually employed for this purpose. All of the said vertically disposed blow-out pipes 3 are supported by and in open communication with the steam supply and distributing pipe 4. This latter pipe is located in the angle between the two sets of flues 2 and 6 and entirely out of the way of both and so as not to be a possible obstruction to either set and where it can be utilized with equal advantage for cleansing said flues. The said pipe is slidable lengthwise or endwise within required limits in suitable guide bearings 7 here and there, and has a rack 8 fixed on its outer end which is engaged by an operating pinion 9 through hand wheel 10 or other suitable means to effect the lengthwise or axial movement of the said pipe.

Steam is supplied from the stationary pipe 11 through the jointed pipe extension 12 to the pipe 4, and a valve having a stem 14 serves to control the flow of steam to the pipe 11. All the said vertical pipes 3 have rollers or casters 15 at their lower free ends which run on tracks 16 and afford both an easy travel and means to confine the said pipes in uniform working position in respect to the flues 2. Of course the back pressure of the steam when blowing out occurs is very strong and the end supports of said pipes 4 must therefore be exceptionally firm to resist such back pressure. It also should be such as to permit comparatively easy hand control of the several parts constituting the complete blow-out installation.

Now, having the distributing pipe 4 mounted in the angle or corner of the two sets of flues 2 and 6, I affix one or more branch pipes 20 to or in said distributing pipe at right angles to the pipes 3 and provide the same with jets or nipples 21 in line with the said flues 6. In the present construction the said pipes 20 are shown in pairs so as to cover the said flues in a single complete movement of the pipe 4, and each pipe 20 is provided with a flanged wheel 22 running on a supporting track 23 at the outer and otherwise free end of said pipe.

It follows that when the steam distributing pipe 4 is moved lengthwise or axially through its rack and pinion control both sets of blow-out pipes are moved in unison 5 through pipe 4 and the tubes 2 and 6 are cleansed simultaneously.

A feature of each vertical pipe 3 with its 10 caster or wheel 15 is the carrier 25 for the said wheel socketed on pipe 4 and provided with downwardly inclined steam jets or 15 nipples 26 adapted to clear the track 16 and corners of dust or other possible constructions.

The angle between the bottom of the 15 boiler front and the outer edge of the exhaust tubes 6 above is covered in by an inclined breeching or housing 30 within which all the foregoing pipes are located, the space 20 inclosed by the said breeching being part of the draftway or passage for the products of combustion which discharge from the flues 2 and pass thence onward to the exit flues 6.

What I claim is:

1. A blow-out installation for boilers 25 comprising a breeching and vertically disposed flues at the top thereof, in combination with a steam distributing pipe slidably mounted in the angle of said breeching and blow-out pipes at right angles to one another carried by said pipe, and means at the free ends of said blow-out pipes adapted to sustain the same against back pressure of the steam and to support the weight of said pipes.

35 2. A blow-out installation for boilers as described comprising a breeching and vertically disposed exhaust flues at the top thereof, in combination with a single steam distributing pipe mounted to slide lengthwise in the angle of said breeching and provided with operating means outside said breeching, blow-out pipes disposed at right angles to each other on said distributing pipe, and means on the free ends of said 40 blow-out pipes adapted to carry the same and thereby relieve the weight on said distributing pipe.

3. In a blow-out installation as described, a breeching and exhaust flues at the top thereof, in combination with a steam distributing pipe slidably supported in the angle of said breeching and provided with sets of blow-out pipes at right angles to each other in front of said boiler and exhaust flues respectively, and supports for 55 said blow-out pipes and a breeching inclosing said pipes.

4. A blow-out installation as described comprising a breeching and vertically disposed flues at the top thereof, in combination with a steam distributing pipe in the angle of said breeching and a plurality of branch pipes thereon in vertical and horizontal sets respectively provided with jets to simultaneously eject steam therefrom, 65 guides in which said distributing pipe is slidably lengthwise and rollers carrying the ends of said branch pipes.

5. An installation as described having a breeching, a steam distributing pipe in the 70 angle thereof adapted to be moved in a direct line and fixed guides therefor and provided with operating means at one end, branch pipes on said distributing pipe at right angles to each other provided with 75 nipples and adapted to be moved simultaneously, a roller on the end of each of said branch pipes and separate tracks for said sets of pipes and rollers.

6. The combination with a smoke box and 80 vertical rows of tubes of different lengths connected thereto, of a cleaner comprising a header longitudinally movable in said smoke-box, and a plurality of laterally extending pipes on said header corresponding 85 in length to the different rows of tubes and provided with jet nozzles for the individual tubes of each row.

In testimony whereof I affix my signature in presence of two witnesses.

DOUGLAS BREWS,
